ESCUTCHEON PLATE FOR PLUMBING FIXTURES OR THE LIKE

William Taylor, 2222 Malcolm Ave., Los Angeles, Calif.,
and Nathan Holzberg, Los Angeles, Calif.; said
Holzberg assignor to said Taylor

Filed Nov. 19, 1962, Ser. No. 72,527

Term of patent 14 years

(Cl. D91—3)

FIG. 1.

FIG. 2.

FIG. 1 is a front elevation view of an escutcheon plate for plumbing fixtures or the like, showing our new design;

FIG. 2 is a side elevation view thereof.

The rear of the design, not shown, is flat and plain except for the open areas.

We claim:

The ornamental design for an escutcheon plate for plumbing fixtures or the like, as shown and described.
